CLAIM

The ornamental design for an extendable jar, as shown and described.

DESCRIPTION

FIG. 1 is a perspective view of the extendable jar, showing our new design;

FIG. 2 is a front view thereof;

FIG. 3 is a top view thereof;

FIG. 4 is a bottom view thereof;

FIG. 5 is an exploded perspective view thereof;

FIG. 6 is a cross-section view thereof taken along 6-6 in FIG. 3 and in an extended position; and,

FIG. 7 is another cross-section view thereof taken along 7-7 in FIG. 3 and in a retracted position.

The extendable jar is shown with a symbolic break in its length. The appearance of any portion of the article between the break lines forms no part of the claimed design.
